YARD ORNAMENT

Rasmus C. Rasmussen, Cushing, Nebr.

Filed Oct. 23, 1963, Ser. No. 77,118

Term of patent 7 years

(Cl. D35—1)

FIG. 1 is a perspective view of a yard ornament showing my new design;

FIG. 2 is a top plan view;

FIG. 3 is a rear elevational view; and

FIG. 4 is a side elevational view thereof.

The textured pattern is understood to continue uniformly throughout the top dome and diamond-shaped areas.

I claim:

The ornamental design for a yard ornament, as shown and described.
